Patented Sept. 9, 1975

236,700

COMBINED TWO-WAY LEVEL AND NAMEPLATE FOR TRAILERS

Charles L. Geiger, 453 Elliot Road,
Clairton, Pa. 15025

Filed Aug. 27, 1973, Ser. No. 391,965

Term of patent 14 years

Int. Cl. D10—04

U.S. Cl. D10—69

Fig. 1.

Fig. 2.

FIG. 1 is a front elevational view of a combined two-way level and nameplate for trailers showing my new design, the rear being plain and unornamented; and

FIG. 2 is a cross-sectional view as taken from line II—II of FIG. 1, the side edges, not shown, being of equal thickness and plain and unornamented.

I claim:

The ornamental design for a combined two-way level and nameplate for trailers, substantially as shown and described.
